CONTAINER VALVE

Stephen D. Hartog, Normandy Township, Mo.

Application July 17, 1937, Serial No. 154,252

5 Claims. (Cl. 221—60)

This specification, aided by the accompanying drawing, discloses certain new and useful improvements in features of construction as well as the means and mode of operation of container valves of the character disclosed in the co-pending application for Container valves, filed June 21, 1937, Serial Number 149,353.

The present invention is related to a container valve in which the valve aperture closure is engaged permanently to the valve for continuous operative employment thereon thereby serving to eliminate the objectionable performance of screwing the aperture closure on and off the container.

15 The primary object therefore of the herein described and illustrated invention is to simplify the construction of container valves in such a novel, economical and operatively efficient manner, that all of the difficulties and incapacities encountered in prior art structures are overcome.

To such ends, briefly summarized, this invention is of and for a container valve characterized by features providing:—

A container valve closure characterized by the feature of having oscillatory movement on a pivot axis and journal bearings of novel construction.

A container valve characterized by the feature of having a closure provided with elongated journal bearings.

30 A container valve characterized by the feature of having a closure provided with journal bearings interrupted by off-set portions forming indentations therewithin.

A container valve characterized by the feature of having a closure operative on a support provided with bearing axes of rectangular form.

A container valve characterized by the feature that the closure portion thereof can be securely locked when moved in one direction and capable 40 of oscillatory movement when moved into a position in opposite direction to that of the first mentioned direction and vice versa in accordance with the desire to lock or unlock the closure.

A container valve characterized by the feature of having a closure support integrally unitary in structure.

A container valve characterized by the feature that the journal bearing axes of the closure support is rectangular in form.

50 A container valve characterized by the feature that all of its parts constituting the structure of the valve are so designed and constructed that they are capable of production by means of die-forming processes, thus insuring economical pro-

duction and accurate duplication and indefinite reproduction.

For the purpose more clearly to understand the expressed objects, and other attending objects, the following description is given, and by aid of the accompanying drawing, it is discernible:

Fig. 1 is a side view in elevation of the valve shown in mounted position on a fragmentary portion of a collapsible tube, the closure portion of the valve being illustrated as in locked engagement on the valve.

Fig. 2 is a side view in elevation of the mounted valve and illustrated as in an unlocked position.

Fig. 3 is an elevation in cross-section of the valve, and there shown mounted on the discharge end of the collapsible tube and in locked position thereon.

Fig. 4 is a view in side elevation when discerned in a position as indicated by the arrow, Fig. 3.

Fig. 5 is a plan view of the aperture closure of the valve.

Fig. 6 is a plan view of the closure support.

Fig. 7 is a view in cross-section of Fig. 6.

Fig. 8 is a plan view of a tubular formed body.

Fig. 9 is a cross-section view in elevation of the tubular formed body, Fig. 8.

Fig. 10 is a plan view of a sealing gasket.

Fig. 11 is a view in cross-section of the gasket.

The parts constituting this container valve are herein designated numerically, and in the order of which 12 identifies a fragmentary portion of a container herein denominated "a collapsible tube."

30 The collapsible tube 12 is provided with a discharge end having an opening 13 surrounded by an embossment 14. On the surface 15 of the embossment there is seated a die-formed metallic slug 16 designed to provide a support. The slug 16 is provided with an aperture 17 located within a portion of the body of the slug which portion is die-formed in such a way that an off-set surface providing a depression 18 is formed within the slug, and an expressed projection 19 is formed on an opposite surface of the slug. Arranged on the slug 16, and integral therewith, 40 are lateral projecting portions 20 and 21 forming limbs providing journal axes 22 and 23, and midway the end of the limbs 20 and 21, and within the body of the slug 16, an opening is made to provide an indentation 24.

50 Within the aperture 17 of the slug, formed to provide a support, a tubular formed body 25 having an enlargement providing a rim 26, is arranged in assembly with the rim 26 of the tubular formed body 25 seated within the depressed por-

tion 18. Thus assembled the extending portion of the tubularly formed body 25 is pressed within the opening 13 of the discharge end of the collapsible tube, and in order to secure the assembly 5 to the tube, a marginal end 27 of the body 25 is crimped or otherwise spun over in such a way as to form a flange and by means of which the assembly is secured to the tube.

There is also included in this valve assembly, 10 a member part providing an aperture closure 28. The closure 28 having rectangularly bent flaps 29 and 30 and within the flaps, journal bearings 31 and 32 are provided, and so formed that offset indentations 33 and 34 interrupt the circular 15 contour of the journals 31 and 32. Formed on the body of the closure 28 is a tang 35,—the tang having a resiliently yielding capacity, the tang 35 being bent to provide a deflected end 36.

At a suitable position on the body of the closure 20 28, angularly bent tabs 37 and 38 are provided; the tab 37 being arranged to provide finger manipulating means for the closure 28, and tab 38, which be it noted is a centrally punched out portion of the tab 37, is formed to provide 25 locking means effected by the claw 39.

The closure thus described is arranged in assembly on the support 16, and the manner of its assembly thereon is effected, firstly: by entering 30 one of the journal axes of the support 16 into one of the journal bearings of the closure, more conveniently accomplished however when the closure is tilted at an angle; secondly: then the other journal bearing of the closure, being aligned with the respective axis of the support 16, is pressed 35 in a manner to permit the resiliently yielding tang 35 to spring into the indentation 24 with the bent end 36 arranged operatively therein, whereby the closure 28 is then so arranged in assembly 40 on the support that no displacement of the closure is possible.

In the drawing the view Fig. 1 shows the closure 28 in locked engagement on the valve, and in the view Fig. 2 of the drawing, the closure is 45 illustrated as in an unlocked position to permit oscillatory movement of the closure 28 in the direction of the arrow line, dotted.

To arrange the closure 28 in locked engagement as shown in Fig. 1, it is necessary to exert sufficient finger pressure on the tab 37, in the direction indicated by the arrow, thereby slidably pressing the closure into a position which permits the axes 22 and 23 to enter the indentations 33 and 34 of the closure journals, and at this instance, the claw 39 will have engaged beneath 55 the surface 16 of the closure support, thereby effecting a locked engagement of the closure 28 on its axis as well as by a latching engagement; in other words, the closure is locked by two independent locking means.

60 The unlocking of the closure is the reverse operation of locking the closure, and the unlocking is brought about by sliding the closure (indicated by the arrow in the view Fig. 2) in the direction which the arrow indicates when finger pressure 65 is exerted upon the tab 37; the closure is then brought to a position in which the axes 22 and 23 enter into bearing contact with the journal bearings 32 and 33 of the closure, at the instance 70 of which, the closure is capable of oscillatory movement in the direction indicated by the dotted lines of the arrow.

It is essential that the closure of the valve be 75 free from leakage, and in order to provide a seal tight joint between the closure and the discharge

aperture, a fabricated gasket 40 is employed, and arranged in assembly on the valve, by seating the gasket into the depression 18, in which position the gasket serves to prevent leakage by forming a seal-tight joint between the surfaces 5 with which it is in contact.

In conclusion, reference is made to the embossment 14 surrounding the aperture 13 of the tube 12. The embossment 14 is of very limited height and so designed and proportioned that a very 10 scant quantity of material is employed in its formation, in consequence of which, an appreciable saving is effected in cost of material over structures requiring a larger volume of material.

Having thus described the invention, it is obvious 15 that there is provided a container valve of the character described and possessed of the advantageous features hereinbefore enumerated as desirable. It is therefore to be understood that the container valve is susceptible of modification 20 in its form, proportions, detailed construction and arrangement of parts without departing from the principle involved or sacrificing any of its advantages.

The invention has been described in language 25 more or less specific as to structural features. It is to be understood, however, that the invention is not limited to the specific details shown, but that the means and construction herein disclosed comprises the preferred form of several modes of 30 putting the invention into effect and the invention therefore is claimed in any of its forms or modifications within the legitimate and valid scope of the appended claims.

I claim, and desire to secure by Letters Patent 35 of the United States of America, this invention as, in, and for:

1. In a collapsible tube valve, a closure provided with journal bearings interrupted by openings 40 providing notched indentations therewithin, journal bearing axes for the closure, the journal bearing axes being capable of entering into the notched indentations when the closure is moved in one direction, the closure being capable of oscillatory movement on the bearing axes when the closure is moved to a position opposite to that of the first mentioned position, and means to secure the valve to the collapsible tube.

2. A container valve comprising a valve aperture closure provided with elongated journal bearings, a closure support having journal bearing axes, the aperture closure being capable of 50 slid-able movement by means of the elongated journal bearings in a direction to lock the closure on the axes of the closure support, the aperture closure 55 being capable of slid-able movement by means of the elongated journal bearings in a direction opposite to the previously mentioned direction thereby permitting oscillatory movement of the closure on its journal bearing axes, means for 60 manipulating the closure, and means to secure the container valve to the container.

3. In a valve suitable for use in connection with containers, the valve comprising an aperture 65 closure provided with elongated journal bearings whereby the closure has movement to open and close the valve aperture, a support for the closure, the support provided with bearing axes, and on which axes the journaled closure is capable of oscillatory movement when surfaces within the 70 closure's elongated journal bearings contact in one direction on the bearing axes of the closure's support, the closure being incapable of movement when the journal bearings of the closure are arranged in a position on the bearing axes of the 75

support opposite to that of the closure's oscillatory position, and means to secure the valve to the container.

4. In a collapsible tube valve, an apertured valve body having journal bearing axes, a closure for the aperture of the valve body, the closure having elongated journal bearings, means within the journal bearing of the closure capable of forming a locked engagement on the valve body 10 when the closure is moved in a direction transverse the longitudinal axis of the collapsible tube, the closure being capable of locked disengagement when moved in an opposite direction, the closure thereby being capable of oscillatory movement on the journal bearing axes of the apertured valve body, means restraining the closure's position while operative on its axes, means for manipulating the closure and means for securing

the valve to the discharge end of the collapsible tube.

5. A collapsible tube valve, a closure provided with cylindrical journal bearings interrupted by openings formed to provide notched indentations therewithin, a support for the closure, said support comprising an integrally unitary metallic slug, the slug provided with portions forming journal bearing axes adapted to enter into the notched indentations formed within the journal bearings of the closure when the closure is moved in one direction, the closure being capable of oscillatory movement on the axes of the slug when moved to a position opposite to that of the first mentioned position, and means to secure the valve 15 to the collapsible tube.

STEPHEN D. HARTOG.
